Improvement in combination cigarette and match case, characterized in that the case is formed of a single piece of plastic material, and the front wall is provided with a tapered rib, parallel with and slightly spaced from the open-

ing, and having a flange, and a dependently attached flange, of relatively small width, and a transverse slot, the tapered rib being positioned in the flange, and the transverse slot being positioned in the dependently attached flange, the flange being positioned to receive the narrow end of a conventional book of matches.

UNITED STATES PATENT OFFICE

2,447,787

COMBINATION CIGARETTE AND MATCH CASE

Orda Q. Atkinson, Lake Worth, Fla.

Application September 20, 1945, Serial No. 617,606

1 Claim. (Cl. 206—38)

1

This invention relates to an improvement in cases for packaged cigarettes and has particular reference to a case adapted to receive a standard package of cigarettes for protection against external pressure and climatic conditions.

A further and very important object of the invention resides in means associated with the case for retaining the conventional package of book matches, such means so arranged and interconnected with the case as to afford the maximum of protection to the matches against moisture.

Another object is the provision of means whereby the cigarettes may be exposed for extraction by a simple pressure upon the match holder and upon release to extend the match holder with its book of matches into a position for convenient removal and striking of a match.

Other important objects and advantages of the invention will present themselves during the course of the following description, reference being had to the accompanying drawings.

Referring to the drawings:

Figure 1 is a perspective view of the combination case, with the parts moved to their operative position in dotted lines.

Figure 2 is a vertical section taken on line 2—2 of Figure 1.

Figure 3 is a horizontal section taken on line 3—3 of Figure 1, and,

Figure 4 is a fragmentary front elevation of the lower end of the case.

Referring specifically to the drawing and wherein is shown the preferred embodiment of the invention, the numeral 5 designates the case as a whole, preferably formed of a conventional plastic material and generally rectangular in cross section. The case is of such size as to receive the conventional package of cigarettes. The case 5 has a closed lower end 6 and an open upper end 7. The open end 7 is normally closed by a cover 8, hinged to the case 5 at 9 and, upon release being moved to the dotted line position of Figure 1, by a spring 10, embodied in the hinge 9. The cover 8 has a depending flange 11, adapted to fit over the upper end of the case 5 when in closed position and the flange 11, upon the front portion, intermediate its ends, is provided with an offset portion 12, having an indentation 13, for a purpose to be described. The case 5 is provided with a substantially rectangular opening 14 in its front wall 5', for a purpose to be described. As clearly shown in Figures 2 and 3, the front wall is provided with a tapered rib 15, parallel with and slightly spaced from the open-

ing 14 and being continuous across the top and the two sides of the opening.

Associated with and permanently attached to the front wall 5' of the case 5, is a book match holder, indicated generally by the numeral 16. The match holder 16 is of such size and shape as to receive and hold a conventional book of matches and further, the holder is of such size as to completely cover the opening 14, when in closed position. The holder 16 is attached to the case by a hinge element 17, surrounded by an actuating spring 18, having one end engaging a fixed portion of the case 5, while the opposite end engages a bottom wall 16' of the holder 16. The holder 16, at its lower extremity is provided with a curved apron 19 to conform to the curvature of the case 5 and a transverse slot 20 is formed in the case to receive the apron 19 when the holder 16 is moved to operative position under the influence of the spring 18. The slot is of such depth as to limit the swinging movement of the holder to a horizontal position.

Intermediate its upper end, the holder is provided with a lip portion 21, extending upward and of such width and length as to engage beneath the offset 12 of the cover, when the parts are in their inoperative position. A lug 22 formed upon the lip 21 is adapted to engage within the indentation of the extension 12 to retain the cover against opening and to prevent the swinging movement of the holder 16. The interengagement of the lug and indentation 13 will prevent the movement of the cover 8, for the reason that such interengagement is maintained by the action of the spring 18 tending to swing the holder 16 outwardly and obviously, the holder cannot swing to the operative position until released from beneath the extension 12. Release of the parts is effected by exerting pressure upon the holder inwardly. As clearly shown in Figure 2, the holder 16 is generally wedge shaped to conform to the shape of the match book and the edges are rounded to generally merge into the contour of the case 5 to give an ornamental appearance. The holder is provided with an inward transverse wedge shaped slot 23, see Figure 2, for receiving the narrow end of the match book, which is wedged therein against displacement, the match book being generally indicated at 24. When the holder is in the closed position, the match book 24 extends through the opening 14 and lies against the package of cigarettes. The purpose of the opening 14 is to reduce the weight and bulkiness of the device. As clearly shown in Figures 2 and 3, the holder is provided with a

wedge shaped groove 25, extending across the top and down the two sides. When the parts are in the inoperative position, there is an interengagement of the rib 15 and groove 25, to more effectively exclude moisture and to retain the parts against undue twisting with the resultant strain on the hinge elements.

In use, it being assumed that the case and holder are loaded and the parts in the position shown in Figure 1. The device is grasped with the fingers against the rear wall of the case and the thumb resting against the face of the holder 16. Pressure exerted by the thumb causes the parts to move inward, releasing the lug 22 from the indentation 13. When this occurs, the spring 10 will automatically swing the cover 8 to open position, at which time a cigarette may be removed. Removal of the thumb from the holder 16, results in the holder being swung to the dotted line position shown in Figure 1, under the influence of the spring 18, at which time the matches are exposed for use in the position normally employed, with the striking surface closest to the operator. The parts are returned to their normal position by first swinging the holder to closed position and then moving the cover 8 to engage over the lip 21, the parts automatically locking against accidental operation in the absence of pressure upon the holder 16.

It is thought that the invention presented herewith is of very novel form, is cheap to manufacture, is strong, durable and highly convenient in use.

Having described the invention, what is claimed is:

A device of the character described for supporting a package of cigarettes comprising a case open at its upper end, a closure cover for said open hinged to the case, a spring for moving the cover to open position, said case having the major portion of its front wall formed open, a book match holder associated with the case and adapted to normally cover the opening in said wall, hinge means between the holder and the case for permitting said holder to swing to open position, a spring for urging the swinging of the holder, an extension carried by the holder to be engaged by the cover and means carried by both the cover and the holder for interengagement to normally retain the cover and holder in closed position simultaneously.
